Application August 3, 1940, Serial No. 350,446

15 Claims.

(Cl. 166—1)

This invention relates to a method and apparatus for setting and cementing liners in wells.

The method and apparatus is primarily used when it is desired to cement the top of the liner in place and to impose a "squeeze job" wherein the cement on being positioned is subjected to high pressure forcing the cement into fissures in the formation and all areas that will receive it.

An object of the invention is to provide a method and apparatus wherein the liner can be run into the well hole and its packer set and tested before commencing the cementing operation. The cement can thereafter be discharged into the annular space between the top of the liner and the well walls or the bottom of the casing and be caused to pass through bypass ports to a point above the top of the liner. In this way the bypass ports allow fresh cement or uncontaminated cement to fill all space possible without undue pressure resistance. When sufficient cement has been discharged the bypass ports can be closed and mud pump pressure applied to force the cement into fissures in the formation and wherever cement will be received. That cement which is initially discharged and which may have become contaminated is flushed up through the bypass ports and through the packer and is not left around the liner so as to be apt to cause a faulty cementing operation. Tailings which are likewise apt to be contaminated are left within the discharge pipe and are not present in the annular space surrounding the liner.

Another object of the invention is to provide a method and apparatus whereby the above-mentioned operations and advantages can be secured by a single run-in of the run-in string of pipe.

A further object of the invention is to provide a bypass port collar or coupling adapted to be incorporated in a liner operable by the run-in string of pipe so that the bypass ports may be opened or closed at will from the surface.

With the foregoing and other objects in view, which will be made manifest in the following detailed description and specifically pointed out in the appended claims, reference is had to the accompanying drawings for an illustrative embodiment of the invention, wherein:

Figure 1 is a partial view in section through the bottom of a well casing illustrating the upper portion of the apparatus embodying the present invention in that position occupied by the parts immediately prior to the setting of the liner;

Fig. 2 is a sectional view illustrating the lower portion of the apparatus which figure may be

considered as a continuation of the lower portion of Fig. 1;

Fig. 3 is a view similar to Fig. 1 illustrating the apparatus in that position assumed by the parts after the liner has been set and its packer expanded against the interior of the casing and in a position just prior to the closing of the ports of the bypass port coupling;

Fig. 4 is a view similar to Fig. 2 illustrating the lower portion of the apparatus in the position shown in Fig. 3 and during that period when cement is being discharged;

Fig. 5 is a view similar to Fig. 1 illustrating the apparatus in the position after the ports of the bypass port coupling have been closed and in the position wherein pressure may be imposed upon the cement to effect the squeeze job;

Fig. 6 is a partial view in vertical section illustrating the details of construction of the bypass port coupling;

Fig. 7 is a horizontal section taken substantially upon the line 7—7 upon Fig. 6 in the direction indicated;

Fig. 8 is a view in vertical section illustrating one form of tubing pack-off coupling that forms a part of the apparatus;

Fig. 9 is a view in vertical section illustrating an alternative form of tubing pack-off coupling that may be employed; and

Fig. 10 is a view in vertical section illustrating the details of construction of the cementing collar that is preferably employed.

Referring to the accompanying drawings wherein similar reference characters designate similar parts throughout, 10 indicates the casing in a well which has been set above the productive formation indicated at F, see Fig. 2. Within the casing it is desired to set and cement a liner. In carrying out the present invention the liner is made up with a lower perforated or slotted section of any suitable length indicated at 11 having an upper portion 12 which is blank or unslotted or unperforated. The lower perforated portion 11 is connected to the upper blank portion by means of a cementing collar 13, the details of which are illustrated in Fig. 10. This cementing collar may be of any preferred design but in the preferred form of construction it has a ported collar 14 having ports 15 within which there is a drillable bushing 16 carrying back pressure valves 17. The bottom of the bushing is blanked off as indicated at 18 preventing downward flow of cement through the bushing and causing it to be expelled outwardly through the walls of the collar 14 past the back pressure valves 17.

A cement basket 19 is optionally mounted on the liner a suitable distance below the cementing collar and serves to prevent cement discharged from the cementing collar from flowing downwardly in the well around the perforated portion 11. A suitable distance above the cementing collar there is incorporated in the liner a tubing pack-off coupling which in the form illustrated in Figs. 2, 4, and 8, comprises an outer collar or coupling 20 threaded at its ends for attachment to the liner sections and having on its interior a rubber ring 21 held in place by means of drillable retaining rings 22 and 23 which may be held in place by means of screws 24. The bore or opening through the rubber ring is such that it may closely fit about a nipple or tail pipe 25, the outlet of which is at the bottom thereof. This ring 21 serves as a type of packing means between the interior of the liner and the exterior of the nipple or tail pipe preventing cement that is discharged from the tail pipe from flowing upwardly between the liner and the tail pipe and causing it instead to be discharged through the cementing collar 13.

At the top of the liner there is incorporated therein a bypass port collar indicated at 26, the details of which are shown in Fig. 6. This bypass port collar is threaded at its ends and is shaped somewhat similar to a reducer. On its interior it is threaded with relatively coarse threads 27 to receive an inner tubular valve 28 which is equipped with complementary threads. This valve preferably carries a packing ring 29 and has secured on its interior a keyed bushing 30. This bushing is held in place by means of screws 31. The interior of the valve 28 is of the same internal diameter as the interior diameter of the liner so that when the keyed bushing 30 which is formed of readily drillable material is drilled up or otherwise removed from the liner on completion of the setting and cementing operations, the valve 28 will form no obstruction on the interior of the liner.

At the upper end of the nipple or tail pipe 25 there are formed two diametrically opposed keys or splines 32 which when the nipple or tail pipe is elevated from the position shown in Fig. 1 to the position shown in Fig. 3 may pass between the keys or splines 33 on the interior of the key bushing 30 so as to enable the keyed bushing to be rotated by the nipple or tail pipe and to thus screw the tubular valve 28 downwardly in the collar or coupling so as to close the ports 34. In the preferred form of construction the interior of the collar or coupling is formed with a seat 35 adapted to be engaged by a complementary seat on the bottom of the valve when the valve is screwed downwardly into the lowermost position.

As will be noted from an inspection of Fig. 7, although the nipple or tail pipe has only two splines or keys 32 which are diametrically opposed the key bushing 30 preferably has three equally spaced keys 33. This construction is to facilitate entry of the splines or keys 32 into the spaces between keys 33 and to provide additional spaces for fluid flow between the key bushing 30 and the nipple or tail pipe 25.

The top of the liner is equipped with a liner hanger which may be of any preferred design. That illustrated comprises a slip cone 36 which serves to expand slips 37 into engagement with the interior of casing 10. Packing means 38 is associated with the liner hanger and is designed to be expanded against the interior of the cas-

ing 10 on the setting of the liner. The run-in string of pipe is equipped at its bottom with a releasing tool consisting of a squared or non-circular tube 39 extending through a nut 40 equipped with left-hand threads 41 engageable with complementary threads on the interior of the liner hanger. An anti-friction bearing 42 is preferably employed to facilitate unscrewing of the nut 41 from the liner hanger regardless of the weight that may be imposed. The nipple or tail pipe 25 is secured to the bottom of the releasing tool and extends downwardly into the liner.

The operation and advantages of the above-described apparatus are as follows. The liner and associated apparatus are first assembled together in the position shown in Fig. 1 wherein the keys or splines 32 on the nipple or tail pipe 25 are disposed below the key bushing 30. The lower end of the tail pipe or nipple slidably extends through the packing ring 21 and is disposed but a short distance above the baffle in the cementing collar 13. In this position the liner is lowered into the well and the apparatus is in that position illustrated in Figs. 1 and 2. On reaching the desired level the slips 37 are released and set as shown in Figs. 3 and 5, and the packing rings 38 are expanded into firm packing engagement with the interior of the casing. When in this position the packer may be tested to determine whether or not it has been properly set and whether or not it is leaking. This is accomplished by imposing mud pump pressure on the outside of the run-in string of pipe and within the casing and observing whether or not pressure builds up therein and is retained.

If the packer 38 has been properly set and there is no indication of leakage the apparatus is then in condition for the cementing operation. The run-in string of pipe is then rotated to the right so as to disconnect the releasing tool from the liner hanger, this being accomplished by unscrewing nut 41 from the liner hanger. The run-in string of pipe can then be lifted a short distance so as to cause the keys or splines 32 to enter the key bushing 30 in the spaces between the keys 33 therein. Cement slurry is then pumped down through the run-in string of pipe and through the nipple or tail pipe 25, being discharged at the bottom of the tail pipe below the packing ring 21. This slurry is caused to exit from the liner through the ports in the cement collar and to flow upwardly around the top of the liner in the annular space between the liner and the well walls. Well fluid, cuttings, and the initially discharged slurry which is apt to be contaminated flow upwardly around the liner and finally into the liner through the bypass ports 34. They then flow upwardly through the spaces between the keys 33 around the nipple or tail pipe 25 and flow upwardly through the liner hanger and through the liner packer 38. In this way all contaminating substances between the liner and the well walls or between the top of the liner and the interior of the casing are effectively flushed out through the bypass ports so that oncoming slurry which is uncontaminated completely fills the annular space surrounding the liner above the cement basket 19. When the cement slurry has been thus positioned around the top of the liner the run-in string of pipe is rotated causing the keys or splines 32 to engage one of the keys 33 thus screwing the tubular valve 28 downwardly closing the bypass ports 34. Mud pump pressure

may then be imposed subjecting the cement that surrounds the liner above the cement basket 18 to high pressure. This causes the cement slurry to enter fissures in the formation and to enter all low pressure areas in the formation whereby a "squeeze job" is imposed to effect a highly efficient cement seal around the top of the liner. Return of the slurry to the interior of the liner is prevented by the bypass ports 34 being closed by the tubular valve 28 and by the back pressure valves 17 in the cementing collar. Consequently, when sufficient pressure has been imposed the run-in string of pipe and its associated apparatus is then in condition to be withdrawn bringing with it the releasing tool and the nipple or tail pipe 25. When the cement has hardened the key bushing 30, the ring 21, and the retaining rings 22 and 23 as well as bushing 16, can be drilled up inasmuch as these parts are all formed of readily drillable material such as aluminum or an aluminum alloy. This leaves the liner cemented in place with the interior of the liner free and unobstructed.

In the event that the liner itself is entirely formed of readily drillable material such as an aluminum alloy, all parts of the liner should be made of readily drillable material where possible. In other words, the tubular valve 28, the body of the bypass port coupling, the body of the pack-off coupling, and the body of the cementing collar should be formed of readily drillable material as well.

It will be noted from the above-described method and apparatus that all operations can be accomplished on a single run-in of the run-in string of pipe, namely the liner may be set and its packer expanded, the packer tested, the space between the liner and the well walls flushed clear and cement slurry discharged in place and subjected to high pressure to effect the "squeeze job." The use of the bypass ports 34 is not only advantageous in enabling the flushing out of contaminating substances but is advantageous in that these ports form an adequate space for the passage of cuttings. In the normal situation the clearance between the packer 32 and the interior of the casing is very small when the packer is in contracted condition, frequently not exceeding $\frac{1}{8}$ ". This small clearance hinders the flushing out of cuttings between the packer and the interior of the casing. By the use of the bypass ports these ports may be adequately large to pass even large cuttings which could not be flushed between the packer and the interior of the casing.

In Fig. 9 there is illustrated an alternative form of pack-off coupling that may be used. In this form of construction the pack-off coupling comprises a coupling body 20a within which there is the rubber or packing ring 21a held in place by means of retaining rings 22a and 23a. Adjacent the bottom of the lower retaining ring 22a there is a valve seat 43 adapted to seat an upwardly closing valve 44 urged into closing position by means of a spring 45. This valve is adapted to be forced open when the tail pipe 25 is passed downwardly through the rubber ring 21a and upon withdrawal of the tail pipe the valve will close so as to prevent reverse flow of the cement slurry. Where this form of construction is used the cementing collar need not be equipped with back pressure valves as valve 44 serves to perform their function. Thus, in using the construction illustrated in Fig. 9 the cementing collar need only be equipped with suitable outlet ports and a baffle therebelow which will cause

the discharged cement to flow outwardly through the outlet ports and not continue down the liner.

From the above-described method and apparatus it will be appreciated that a highly improved means and method has been developed for setting and cementing liners in wells.

While the improved means and method has been primarily designed to enable the displacing of well fluid from around the liner by uncontaminated cement slurry and the imposition of pressure to effect a "squeeze job" it will be understood that it is not necessary in all instances to impose pressure. In some situations the method and apparatus may be advantageously employed without attempting the imposing of pressure to secure a "squeeze job."

Various changes may be made in the details of construction without departing from the spirit or scope of the invention as defined by the appended claims.

We claim:

1. The method of setting and cementing liners in wells which includes setting the liner in a well, packing off between the top of the exterior of the liner and the interior of the well casing, discharging cement in the liner and forcing it to the exterior thereof and causing flow upwardly on the outside of the liner, then into the liner, and upwardly through the packer, and then closing the upper entrance to the liner against flow therethrough and imposing pressure on the cement on the exterior of the liner.

2. The method of cementing liners in wells which includes setting the liner in a well, discharging cement in the liner and forcing it through a lower outlet therefrom to the exterior of the liner to cause upward flow on the outside of the liner and into the liner through an upper inlet, and then closing the upper inlet and imposing pressure on the cement on the exterior of the liner.

3. The method of cementing liners in wells which includes setting the liner in a well, discharging cement in the liner and forcing it to the exterior thereof through a lower outlet and preventing upward flow from adjacent the lower outlet within the liner, causing upward flow on the outside of the liner and from the exterior of the liner into the liner through an upper inlet, and then closing the upper inlet against inward flow therethrough and imposing pressure on the cement on the exterior of the liner.

4. An apparatus for setting and cementing liners in wells including a liner, packing means for packing off between the top of the liner and the interior of a well casing, a run-in string of pipe detachably connected to the liner having a nipple extending into the liner, a second packing means for packing off between the interior of the liner and the nipple above the outlet from the nipple, there being an inlet to the liner between the packing means, and means for optionally opening and closing said inlet.

5. An apparatus for setting and cementing liners in wells including a liner, packing means for packing off between the top of the liner and the interior of a well casing, a run-in string of pipe detachably connected to the liner having a nipple extending into the liner, a second packing means for packing off between the interior of the liner and the nipple above the outlet from the nipple, there being an inlet to the liner between the packing means, and means for optionally opening and closing said inlet operable by the nipple.

6. An apparatus for setting and cementing liners in wells including a liner, packing means for packing off between the top of the liner and the interior of a well casing, a run-in string of pipe detachably connected to the liner having a nipple extending into the liner, a second packing means for packing off between the interior of the liner and the nipple above the outlet from the nipple, there being an inlet to the liner between the packing means, and means for optionally opening and closing said inlet operable by rotation of the nipple by the run-in string of pipe.

7. An apparatus for setting and cementing liners in wells comprising a liner having external packing means adjacent its top adapted to be expanded into engagement with a well casing, a run-in string of pipe detachably connected to the liner by which the liner may be lowered into the well and the packing means set, there being inlet ports in the liner beneath the packing means, a nipple connected to the run-in string of pipe extending into the liner, means for packing off between the interior of the liner and the nipple above the outlet from the nipple, a cementing collar equipped with back pressure valves in the liner below the last-mentioned packing means, a cement basket on the liner below the cementing collar, and valve means operable by the nipple for closing the inlet ports to the liner.

8. An apparatus for setting and cementing liners in wells comprising a liner having external packing means adjacent its top adapted to be expanded into engagement with a well casing, a run-in string of pipe detachably connected to the liner by which the liner may be lowered into the well and the packing means set, there being inlet ports in the liner beneath the packing means, a nipple connected to the run-in string of pipe extending into the liner, means for packing off between the interior of the liner and the nipple above the outlet from the nipple, a cementing collar equipped with back pressure valves in the liner below the last-mentioned packing means, and valve means operable by the nipple for closing the inlet ports to the liner.

9. A bypass port collar for use in cementing liners comprising a ported collar adapted to be incorporated in a liner, a tubular valve threaded into the collar adapted to be screwed into positions opening or closing the ports, and means on the valve engageable by a nipple attachable to a run-in string of pipe by which the valve may be screwed.

10. A bypass port collar for use in cementing liners comprising a ported collar adapted to be incorporated in a liner, a tubular valve threaded

5 into the collar adapted to be screwed into positions opening or closing the ports, and means on the valve engageable by a nipple attachable to a run-in string of pipe by which the valve may be screwed, the collar having a seat against which the valve may be tightened.

11. The method of setting and cementing liners in wells which includes setting the liner in a well, packing off between the top of the exterior of the liner and the interior of the well casing, discharging cement in the liner and forcing it to the exterior thereof and causing flow upwardly on the outside of the liner, then into the liner, and upwardly through the packer, and then closing the upper entrance to the liner against flow therethrough.

12. The method of cementing liners in wells which includes setting the liner in a well, discharging cement in the liner and forcing it through a lower outlet therefrom to the exterior of the liner to cause upward flow on the outside of the liner and into the liner through an upper inlet, and then closing the upper inlet.

13. The method of cementing liners in wells which includes setting the liner in a well, discharging cement in the liner and forcing it to the exterior thereof through a lower outlet and preventing upward flow from adjacent the lower outlet within the liner, causing upward flow on the outside of the liner and from the exterior of the liner into the liner through an upper inlet, and then closing the upper inlet against inward flow therethrough.

14. The method of cementing liners in wells which includes setting the liner in a well, discharging cement in the liner and forcing it through a lower outlet therefrom to the exterior of the liner to cause upward flow on the outside of the liner and into the liner through an upper inlet, and then closing the upper inlet and drilling out the interior of the liner so as to leave its interior open and unobstructed.

15. An apparatus for cementing liners and the like in wells comprising a liner having an outlet and an inlet thereabove, means detachably connecting the liner to a run-in string of pipe, a nipple connected to the run-in string of pipe and extending into the liner to a level below the inlet, means for preventing upward flow between the liner and the nipple to cause the cement discharged through the nipple to pass out of the outlet, a threaded valve operable upon rotation to close the inlet, and means providing a splined connection between the nipple and the valve.
